UNITED STATES PATENT OFFICE.

OTTO W. LINQUIST, OF PASKIN, WISCONSIN.

TATTING-SHUTTLE.

1,206,555.

Specification of Letters Patent. Patented Nov. 28, 1916.

Application filed April 26, 1916. Serial No. 93,683.

To all whom it may concern:

Be it known that I, OTTO W. LINQUIST, a citizen of the United States, residing at Paskin, in the county of Barron and State 5 of Wisconsin, have invented new and useful Improvements in Tatting-Shuttles, of which the following is a specification.

This invention relates to tatting shuttles and has for an object the provision of a 10 shuttle embodying means for supporting the tatting thread for convenient use by the operator or user.

Another object of this invention is to provide a tatting shuttle in which the tatting 15 thread may be readily wound on its bobbin, and the operating means being adapted to be folded to and from operative position or to be folded within the general contour of the shuttle.

20 A further object of the present invention is to provide a tatting shuttle of generally improved construction, whereby the device will be simple, durable and inexpensive in construction, as well as convenient, practical, serviceable and efficient in its use.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without departing from the spirit of the invention.

The invention has been illustrated in the preferred embodiment, in the accompanying drawings wherein:—

40 Figure 1 is an elevational view of the improved tatting shuttle, Fig. 2 is a longitudinal sectional view therethrough, Fig. 3 is a transverse sectional view taken on the line 3—3 of Fig. 1.

45 In carrying out the present invention, there are provided opposed side members 1, one of which has a longitudinal slot 13 formed therein. A tubular shaft or post 2 is secured between the side members and 50 has rotatably mounted thereon a bobbin or spool which comprises an intermediate tubular portion 3 thereof. The tubular portion 3 has its opposite ends formed with flanges which are round in elevation and 55 one of these flanges is toothed to mesh with the gear 7 that is secured to a stub shaft 8

which is rotatably mounted in a suitable bearing 9, which, is in turn supported by the slotted side member 1.

Pivots secured to the outer terminal 60 of the stub shaft 8 is a crank 10 having a knob or manipulating finger 12 extending from the free end thereof. Any suitable means may be provided for attaching the thread to the spool or bobbin and, in the 65 present instance, there is provided a resilient hook 14 which is secured to the intermediate tubular portion 3 of the said bobbin.

In practical operation, the thread is readily secured to the bobbin, after which, rotary motion is imparted to the bobbin by simply rotating the crank 10. This movement will rotate the stub shaft 8 and gear 7 and consequently impart the desired rotary motion to the entire spool, since its 75 toothed flange 6 is in mesh with the gear 7. After a sufficient quantity of thread has been wound upon the bobbin, the crank 10 is swung about its pivot 11 until it is housed within the longitudinal slot 13. In this position, the knob or manipulating finger 12 is also received within one terminal of the tubular shaft 2; therefore, providing a shuttle of uninterrupted contour.

It is manifest that this shuttle may be 85 advantageously employed in tatting, or other functions to which this device may be adapted, since no obstructions extend beyond the outer face of the side pieces 1, thus enabling it to be readily inserted 90 through the meshes of the formed material. The operator is, also, enabled to maintain the proper thread tension, because when the crank or rotating member 10 is moved to inoperative position within the longitudinal 95 slot 13, then the entire bobbin is locked against rotation, and consequently, prevents the thread from being inadvertently drawn from the bobbin.

Having thus described my invention, what 100 is claimed as new is:—

1. A shuttle including side pieces, a transverse shaft secured between the said side pieces, a bobbin rotatably mounted on the shaft and comprising an intermediate tubular portion and spaced flanges, one of the said flanges being toothed, a bearing member supported by one of the side pieces, a stub shaft rotatably mounted in the said bearing member, a gear secured to the stub 105 shaft and adapted to operably engage the toothed flange of the bobbin, a crank piv-

totally secured to the stub shaft and adapted to be moved about its pivot to and from operative position, and a resilient hook carried by the bobbin and adapted to secure the thread to the said bobbin.

2. A shuttle including side pieces, one of which having a longitudinal slot formed therein, a tubular shaft secured between the side pieces, a bobbin rotatably mounted upon the tubular shaft and having a toothed flange extending therefrom, a stub shaft rotatably supported by the slotted side pieces, a gear secured to the stub shaft and adapted to operably engage the said toothed

flange, a crank pivotally secured to the stub shaft, said crank being received by the longitudinal slot when it has been moved to its inoperative position, a manipulating finger secured to the outer terminal of the crank, said finger extending into one terminal of the tubular shaft when the crank is in its inoperative position.

In testimony whereof I affix my signature in presence of two witnesses.

OTTO W. LINQUIST.
